UNITED STATES PATENT OFFICE.

MALCOLM WILLIAM PARKER, OF EAST MALVERN, VICTORIA, AUSTRALIA.

LAST FOR PUMP SHOES.

Application filed March 23, 1926, Serial No. 96,734, and in Australia May 11, 1925.

My invention relates to improvements in lasts for the manufacture of pump shoes (which are also known as turn shoes), which are more particularly in use as footwear for 5 women, and the object of my improvements is to provide means for obtaining the desired shapes of shoes without undue straining or distortion of the material so as to minimize the percentage of rejects and increase the ease of re-lasting during manufacture and so as to facilitate the designing of the upper. I attain this object by the means illustrated in the accompanying drawings in which,

15 Figure 1 is a diagrammatic elevation of the last used in the first lasting of the shoe, according to my invention, the shape of the normal last being shown in dotted lines and the allowance which would be made for the 20 sole if there were no contra allowance for the shank being shown in chain lines.

Figure 2 is an enlarged cross-section on the line 2—2 of Figure 1, showing in dotted lines the positions of the turned shoe and of 25 the last used in the second lasting process.

Figure 3 is a fragmentary cross-sectional view, still further enlarged, showing the relative positions of the sole, upper and last during the second lasting process.

30 In the manufacture of a shoe, the normal practice is followed of first channeling the sole 16 on the inside so as to form a shoulder 20 and an inside channel 21. The sole 16 is then placed with its outer side resting on the last 17 and the upper 18 is then drawn over the last and its edges are temporarily secured to the inner face of the sole by tacks 19. The "stiffener" (or heel support), "toe" (or toe support) and the lining are 35 also positioned temporarily by the same means, as is well known, being on the outside in relation to the last. The shoe is then sewn, the temporary tacks removed, and the surplus materials trimmed off. It 40 is next turned and, after insertion of the "shank" (or waist support), is pulled on to the last 23. The "toe", "stiffener" and "shank" are formed generally of sole leather or of a synthetic preparation.

45 When the shoe is first lasted inside out, the "stiffener", "toe" and lining are on the outside of the shoe, and when turned and the "shank" inserted the "stiffener", "toe", lining and "shank" will be on the inside. According to previous practice the lasts 17 and 23 50 were the same size and shape with the ex-

ception that the last 17 used in the first lasting might be made larger than the last 23 by an amount equivalent to the "shank", which amount made provision for the subsequent insertion and attachment of the shank. I have observed that if the lasts 17 and 23 are of the same size and shape the material of the shoe becomes strained or distorted by displacement during the second lasting by an amount equal to the 60 spaces occupied by the "stiffener", "toe" and lining. On the other hand, I have realized that, as the upper 18 during the first lasting is secured to the side of the sole 16 which 65 is further from the last 17, the space between the upper 18 and the sole 16 when the shoe is turned will be larger than the last 17.

According to my invention, the normal last 23 shewn in dotted line in Figures 1 and 2 70 is used in the second lasting while the last 17 used in the first lasting is shaped as shewn in full lines in Figure 1. In this figure the space 1, 2, 3, 4 represents vertically the deduction which I make from the 75 first-lasting last in order to allow for the subsequent out-turning of the sole. The space 1, 5, 6, 7 represents vertically the enlargement of such last which must be made if it is desired to make allowance also for 80 the subsequent inturning of the "toe" and this enlargement will extend to the point 8 on each side of the shoe. The space 9, 10, 11, 12 represents the allowance which would 85 be made for the subsequent insertion of the shank but from this must be subtracted the opposite allowance 9, 13, 3, 4 for the outturning of the corresponding portion of the sole, leaving a differential space 13, 12, 11, 3 representing the amount by which such 90 last must be enlarged at this part. The 95 enlargement 14, 11, 15 provides for the subsequent in-turning of the "stiffener". As it is not usually necessary to make allowance for the subsequent in-turning of the 100 lining, this feature is not illustrated. The allowance for the "toe" is not usually so important as that for the "stiffener".

This invention, accordingly, results in the 105 production of stronger footwear of this type, with a much smaller percentage of rejects, and with greater ease of re-lasting during manufacture. Further, the invention facilitates the designing of the upper, because the form taken off this first-lasting last is true 110 to the final shape on account of such provision for the thickness of the "stiffener" and

other parts above mentioned. It is obvious that, according to this method, the first-lasting last is usually an exact reproduction of the normal last (which in this method is not used until the second lasting) with a reduction which makes allowance for the sole and enlargements which make allowance for the other parts above mentioned. The enlargements will normally be integral with the last.

I claim:—

1. Means for the first-lasting of pump shoes, comprising a last having an enlargement thereon at a position corresponding to

the position of the "stiffener" of the shoe in combination with a reduction corresponding to the position of the fore part of the sole of the shoe, substantially as described.

2. Means for the first-lasting of pump shoes, comprising a last having enlargements thereon at positions corresponding to the "stiffener" and "toe" of the shoe in combination with a reduction corresponding to the position of the fore part of the sole of the shoe, substantially as described.

In testimony whereof I affix my signature.

MALCOLM W. PARKER.
